(57) **CLAIM**

The ornamental design for a display screen or portion thereof with graphical user interface, as shown and described.

DESCRIPTION

The sole FIGURE is a front view of a display screen or portion thereof with graphical user interface, showing the new design.

The dot-dash broken lines in the FIGURE show a display screen or portion thereof and form no part of the claimed design. The remaining broken lines in the drawings, including evenly spaced broken lines and all lined-through text, show the display screen or portion thereof, or an electronic device having a display screen or portion thereof, and form no part of the claimed design.
